UNITED STATES PATENT OFFICE.

WARREN DOBSON GALE, OF WATERVILLE, QUEBEC, CANADA.

INTERNAL-COMBUSTION ENGINE.

1,103,282.

Specification of Letters Patent. Patented July 14, 1914.

Application filed August 5, 1912. Serial No. 713,401.

To all whom it may concern:

Be it known that I, WARREN DOBSON GALE, a subject of the King of Great Britain, and a resident of Waterville, in the Province of Quebec, in the Dominion of Canada, have invented certain new and useful Improvements in Internal-Combustion Engines; and I do hereby declare that the following is a full, clear, and exact description of 10 the same.

The invention relates to improvements in internal combustion engines, as described in the present specification and illustrated in the accompanying drawings that form part 15 of the same.

The invention consists essentially in the novel construction and arrangement of parts, whereby the inlet and exhaust ports are expeditiously opened and timed by a 20 peculiar arrangement of valves and operating gear.

The objects of the invention are to eliminate as far as possible the delay frequently incident to the opening of a port, either for 25 inlet or exhaust purposes, to construct a very simple engine cheap to manufacture and efficient in its operation and generally to improve in this particular class of engines.

In the drawings Figure 1 is a vertical 30 sectional view of the engine showing the valve in longitudinal section. Fig. 2 is a cross sectional view of the head and the valves. Fig. 3 is an end view of the valve gear. Fig. 4 is a vertical sectional view of 35 the engine showing multiple cylinders.

Like numerals of reference indicate corresponding parts in each figure.

Referring to the drawings, 1 are the cylinders having the integral heads 2 and supported 40 on the crank chamber casing 3 and surrounded by the water jackets 4, said heads having the valve chambers 5 and 6 extending clear through from the extremity of the head of the cylinder at one end to the 45 extremity of the head of the cylinder at the other end or in the case of a one cylinder engine just through the head, the circular bores forming said chambers 5 and 6 tapering from one end to the other.

50 7 are inlet ports to the cylinders 1 from the valve chamber 5.

8 are exhaust ports from the cylinders 1 to the valve chamber 6.

9 are spark plug holes in the web of the heads 2 between the valve chambers 5 and 6. 55

10 are pistons operating in the cylinders 1 and connected to the crank shaft 11 by the piston rods 12, said crank shaft 11 being journaled in the bearings 13 in the casing of 60 the crank chamber 3.

14 is the valve gear chamber at one end of the cylinders 1 and formed of the plate 15, secured to the end of the engine by the bolts 16 and having the valve hole 17 adjacent to the upper end and the crank shaft hole 18 adjacent to the lower end, the outwardly extending flanged wall 20, secured to the plate 15 by the bolts 21 and gradually narrowing said chamber 14 from the upper to the lower end, 65 and the outer cover plate 22 secured to the outside flange of the wall 20 by the bolts 23.

19 is a stub shaft secured to the side of the crank casing just above the crank shaft bearing.

24 is a spur gear wheel journaled on the 75 shaft 19 and having the hub 25 extending inwardly therefrom.

26 is a sprocket wheel fixedly mounted on the hub 25.

27 is a spur gear wheel fixedly mounted 80 on the crank shaft 11 in the gear chamber 14 and coating with the spur gear 24 therefore it will be seen that during the operation of the crank shaft 11, through its connection with the pistons 10, the spur gear 24 is 85 rotated and consequently the sprocket wheel 26.

28 is a sprocket wheel fixedly mounted on the crank shaft 11.

29 is a tapered hollow rotary valve closed 90 at its smaller end and suitably connected with the main inlet at its other and open end.

30 are ports in the wall of the valve 29 adapted to register with the inlet ports 7. 95

31 is a thread formed on the valve 29 adjacent to the smaller end the open end of said valve being adapted to be connected to the explosive mixture supply.

32 is a sleeve valve encircling the valve 100 29 and having the ports 33 registering with the ports 30 and the ports 7, said valve 32

being open at both ends and having the thread 34 adjacent to its smaller end. The valve 32 fits closely in the valve chamber 5, the walls of said chamber forming a bearing 5 in the rotation of said valve. The inner wall of the sleeve valve 32 forms a bearing for the valve 29 and the smaller end of the latter valve extends beyond the end of the said sleeve valve 32 into said valve gear chamber 14.

35 is a nut screwed on to the thread 34 against the end of the cylinder head.

36 is a lock nut holding the nut 35 in place.

15 37 is a sprocket wheel fixedly mounted on the sleeve valve 32 at the smaller end thereof and connected to the sprocket wheel 26 by the chain 38, therefore on the rotation of the spur gear 24 through its connection 20 with the spur gear 27 of the crank shaft 11 the sleeve valve 32 is rotated in one direction, that is to say, in an opposite direction to the direction of rotation of the crank shaft.

25 39 is a nut screwed on to the thread 31 against the end of the sleeve valve 32.

40 is a lock nut securing said nut 39 in place.

41 is a sprocket wheel fixedly mounted 30 on the smaller end of the valve 29 and connected to the sprocket wheel 28 by the chain 42 therefore the valve 29 is rotated in the same direction as the crank shaft 11 and in an opposite direction to the sleeve 35 valve 32 consequently it will be seen that the valves 29 and 32 turning in opposite directions insure a quick full opening for the ingress of the explosive mixture.

43 is a similar valve to the valve 29 40 and is encircled by the sleeve valve 44 said valves being inserted in the valve chamber 6 and secured exactly the same way as valves 29 and 32 the chains 38 and 42 passing over sprocket wheels mounted at 45 the ends of said valves, said chains forming the connecting means for operating both the inlet and exhaust valves, the valves 43 and 44 being so set to have their ports register with the exhaust ports 8 in proper 50 time according to the movements of the pistons.

The valve gear chamber 14 is filled or partially filled with oil so that the operating parts therein are well lubricated. 55 Further lubrication of the engine is not described herein as any well known system may be used.

In the operation of this engine explosions are started as customary in internal 60 combustion engines and the rotation of the crank shaft brings the inlet ports 7 into register with the ports 30 and 33 through the sprocket and chain connections from the

crank shaft to the valves 29 and 32, these valves turning in opposite directions the 65 ports 33 and 30 meet and travel toward one another with the result that a complete opening is made in very quick time opposite said inlet ports 7. The explosive mixture now enters and the cycle of movements is complete when the exhaust valves 70 operating in chambers 6 bring their ports into alignment with the exhaust ports 8 from cylinders, the spent gases flowing through the valve 43 out through the open 75 end thereof.

Simplicity of the parts of this engine just described constitute its chief merit while the operation thereof is certain and quick for full clear openings at the inlets 80 are assured as also are full clear openings at the outlets.

It will be seen that the ports in the valves are larger than the ports from the cylinders therefore proper timing may be assured. 85

What I claim is:—

In an internal combustion engine, in combination, a plurality of cylinders having across the heads thereof a pair of circular valve casings extending continuously from 90 one end cylinder to the other end cylinder and gradually diminishing in diameter from one end to the other end, said casings having inlet and exhaust ports respectively to and from the cylinders, the said heads 95 being recessed between said chambers and having a spark plug opening at the bottom of said recesses leading into each cylinder between said ports, one of said casings at its larger end being connected to 100 the inlet pipe and the other of said casings at its larger end being connected to the exhaust pipe, a set of tapered sleeves telescopically arranged in each of their casings and rotating in opposite directions respectively, the outer of said valves being open at both ends, and the inner of said valves being closed at the smaller end, each of said valves having external threads at the smaller ends, said smaller ends projecting 105 beyond the cylinder, said valves having inlet and exhaust ports adapted to meet in rotation and register, a nut and lock nut on each of said outer sleeves at the smaller ends forming retaining members abutting 110 the end walls of said casings, a nut and lock nut on each of said inner sleeves at the smaller ends thereof abutting the smaller ends of said outer sleeves, sprocket wheels 115 fixedly mounted on the four sleeves, a sprocket wheel fixedly mounted on the crank shaft, a chain connecting said sprocket on the crank shaft with two of the aforesaid sprockets and auxiliary shaft gears connecting said auxiliary shaft and said crank 120 shaft, a sprocket on said auxiliary shaft,

125

a chain connecting said sprocket on the auxiliary shaft with the other two of the twelve.

5 sleeve sprockets, a crank shaft, pistons operating in said cylinders and piston rods connecting said pistons to said crank shaft.

Signed at the city of Sherbrooke in the Province of Quebec this twenty seventh day

of June one thousand nine hundred and twelve.

WARREN DOBSON GALE.

In the presence of—

E. B. WELLINGTON,

ALEXINA JONEAS.
